UNITED STATES PATENT OFFICE.

FRANK MALOCSAY, OF NEW YORK, N. Y., ASSIGNOR, BY MESNE ASSIGNMENTS, TO SONORA PHONOGRAPH COMPANY, INC., A CORPORATION OF NEW YORK.

TALKING MACHINE.

Application filed May 24, 1915. Serial No. 30,066.

To all whom it may concern:

Be it known that I, FRANK MALOCSAY, a citizen of the United States, residing in the borough of the Bronx, county of Bronx, city and State of New York, have invented certain new and useful Improvements in Talking Machines, of which the following is a specification.

My invention relates to talking machines, and particularly to those of the disc record type and has for its object to produce a device whereby an operator on such a talking machine will be able to tell at a glance the amount of spring power the motor contains at any time, and how many records may be run off before it will be necessary to rewind the motor.

A further object is to produce a device which will indicate when the motor is completely wound.

A further object is to provide means for locking the motor against rotation when there is not sufficient power in the motor to play a full record.

These and further objects will more fully appear in the following specification and accompanying drawing, considered together or separately.

I have illustrated my improved device in the accompanying drawing, in which:

Fig. 1 is a front elevation of a talking machine.

Fig. 2 is a plan view with the cover removed.

Fig. 3 is a plan view with parts broken away.

Fig. 4 is a similar view showing the parts in a different position.

Fig. 5 is a detail sectional view taken on the line 5—5 of Fig. 3.

Fig. 6 is a similar view taken on the line 6—6 of Fig. 3.

Fig. 7 is a similar view taken on the line 7—7 of Fig. 3.

Fig. 8 is a section on the line 8—8 of Fig. 5, and

Fig. 9 is a section on the line 9—9 of Fig. 5.

In the drawings in which the same parts in all of the several figures are designated by similar reference characters, 1 designates a cabinet wherein is contained the operating mechanism and horn of a disc record talking machine. The cabinet is provided with a hinged cover. Secured

within the cabinet and across the upper part thereof is a horizontal partition 2 to the under side of which a motor is secured. The motor comprises the usual spring drums 3 and 4 to one of which a spur gear 5 is attached. The gear is engaged by a pinion 6 on a winding shaft 7 which projects through the side of the casing and is engaged by a crank in any well known manner. The spring drum 4 is provided with a gear 8 which, through a gear train in which is located the usual governor, drives a spindle 9 which projects through the partition 2 and carries a turn-table 10 which in turn supports a record disc 11.

The winding shaft 7 is provided with a ratchet wheel 12 which is engaged by a pawl 13 to prevent backward movement of the shaft. A portion 14 of the shaft has a left handed screw thread and carries a nut 15 which is the hub of a spur wheel 16. The hub is extended on both sides of the gear 16 and carries a yoke 17 which extends upward and projects through a slot 18 in the motor frame.

Carried in the motor frame and located above the threaded portion of the winding shaft 7 is a shaft 19 which is provided with pinion 20. This pinion has a face of a length approximately equal to that of the threaded portion of the shaft 7 and is engaged by the teeth of the gear 16. The shaft 19 carries at one extremity thereof a gear pinion 21 meshing with a gear 222 carried by the drum 4.

The upper end of the yoke 17 above the frame has pivoted thereto a lever 22 to which is pivoted an arm 23 which extends across the motor frame and is pivoted on the spindle 9. The free end of the arm projects upward through a slot 24 in the partition and is provided with an indicator finger 25 which co-operates with a scale 26 on the partition. The scale is calibrated to read four large records and six small records. The lever 22 extends beyond the pivot of the arm 23 and is provided with a slot 27 through which projects the free end of a bar 28. The bar 28 is pivoted to a lever 29 which is carried on a shaft 30 which passes through the partition. The upper end of the shaft 30 carries a brake shoe for engagement with the turn-table to hold the latter against the action of the motor. A spring 31 anchored to the lever 29 bears against

the bar 28 to normally hold it in engagement with one end of the slot 27. Carried on the motor frame is a stop 32 provided with a notch 33 to receive the free end of the bar 28.

The partition 2 carries the usual speed indicator and the fitting for the tone arm.

The operation of my improved device is as follows:

- 10 When the motor is being wound the nut 15, and with it the gear 16 and the yoke 17, will be moved to the right in Fig. 3 by the threads 14 until the winding is completed when the parts will be in the positions shown
- 15 in Figs. 2, 3, and 5. The yoke will be in the left hand end of the slot 18, the bar will be moved away from the stop 32, the brake will be in engagement with the turn-table, and the indicator finger 25 will be at the extreme right of the slot 24 and indicate on the scale 26 that there is enough power in the motor to run off four large or six small records. It will be understood that in winding the springs the gear 16 will be held
- 20 against rotation by means of its engagement with the long face pinion 20, and will be moved across the face of the pinion. When it is desired to operate the machine a record disc is placed upon the turn-table, the tone-
- 25 arm is swung out, and the sound-box is swung down with its needle resting in the record groove. The brake is now released and the motor will rotate the turn-table in the clock-wise direction. As the springs un-
- 30 wind the gear 222 will rotate the pinion 20 through the pinion 21. The gear 16 will rotate through its engagement with the pinion 20, and as the shaft 14 is held against rotation by the pawl and ratchet, the nut 15
- 35 and yoke 17 will be fed to the left in Fig. 5 by the screw threads 14 on the shaft.

As the nut and yoke move to the left in Fig. 5, the parts will be travelling in the opposite direction as viewed in Fig. 3. The yoke will move to the right in Fig. 3, and carry with it the short leg of the arm 23, and the bar 28. The finger 25 will move to the left, and by its position will indicate the number of records which may be run off before it will be necessary to rewind the motor. The bar 28 will be caused to follow the movement of the lever 22 by means of the spring 31.

When the finger 25 reaches the position shown in Fig. 4, it will indicate that there is not enough power in the motor to run the full record on a large disc, but has just enough to finish the record. The lever 22 has been moved to nearly its extreme position to the right, and the free end of the bar 28 will rest against the stop 32, as shown in dotted lines Fig. 4. The motor will continue to run the record out, and the further movement of the lever 22 will not affect the bar 28 owing to the slot 27. When the record

is finished, there will still be a small amount of surplus power left in the motor, and to prevent the needle from scratching the record surface, it is necessary to apply the brake to hold the turn-table stationary, 70 while the record is being removed and a new one substituted.

When the brake is applied, the lever 29 will swing down, and the end of the bar 28 will drop into the notch 33, and the brake 75 shoe will be locked in engagement with the turn-table and cannot be released until the motor has been rewound to an extent at least to move the arm 23 to the right of the mark "Large I" on the scale 26. When the motor has been rewound to that extent the lever 22 will be moved to the left so that the right hand end of the slot 27 will have pushed the end of the lock bar out of the notch in the stop and the brake shoe may be released 80 from engagement with the turn-table.

By means of my improvement, the operator can tell by glancing at the scale exactly how many records may be played without rewinding, and should he neglect to notice the scale, he will be assured that when he places a record on the turn-table and releases the brake, that the record will be run to its full course.

In accordance with the provisions of the Patent Statute, I have described the principle of my invention together with the apparatus which I now consider to represent the best embodiment thereof, but I desire to have it understood that the apparatus 95 shown is merely illustrative, and that the invention can be carried out in other ways without departing from the spirit of my invention.

Having now described my invention what 105 I claim as new and desire to secure by Letters Patent of the United States, is as follows:

1. In a talking machine, the combination with a record carrier, of means for rotating said record carrier and means for controlling the stopping and starting of said rotating means, of means for rendering said controlling means inoperative to start the rotation, when the record carrier has been rotated to a predetermined extent. 110
2. In a talking machine, the combination with a record carrier, means for rotating said record carrier, a brake for holding said record carrier against rotation, and means for moving said brake to an inoperative or released position, of means for rendering said brake moving means inoperative to move the brake from its set or applied position when the record carrier has rotated to a predetermined extent. 115
3. In a talking machine, the combination with a record carrier, means for rotating said record carrier, a brake for arresting 120 the rotation of the record carrier, and means

for automatically locking said brake against release when the carrier has rotated to a predetermined extent.

4. In a talking machine, the combination with a spring motor, means for winding the spring, of a brake for arresting the unwinding of the spring, and means for locking the brake in operative position when the spring has unwound to a predetermined extent, and means for indicating when the brake is in locked position.

5. In a talking machine, the combination with a spring motor, means for winding the spring, of a brake for arresting the unwinding of the spring, and means for locking the brake in operative position when the spring has unwound to a predetermined extent, and visual means for indicating when the brake is in locked position.

6. In a talking machine, the combination with a spring motor, a brake, a winding shaft, for the motor, screw threads on the shaft, a nut engaging the threads, a gear on the nut, and a long faced pinion in mesh therewith, means for rotating the long faced pinion by the unwinding of the spring whereby the gear will be caused to travel longitudinally of the shaft, a yoke actuated by the travel of the gear, of a lever pivoted to the yoke, an arm pivoted to the lever, a pointer on the arm, a scale co-operating with the pointer, a bar carried by the brake, a stop for engaging the bar, and means carried by the lever for disengaging the bar from the stop.

7. A talking machine according to claim 1, and means for indicating the number of records that can be played before said controlling means is rendered inoperative.

8. The combination in a phonograph with a rotating record carrier, of a plurality of calibrations for different size records and a single indicator coacting therewith for indicating purposes, said calibrations and said indicator having relative movement in synchronism with the movement of the record carrier.

9. The combination in a phonograph with a rotating record carrier, of a plurality of calibrations for different size records, and means coacting therewith for indicating purposes, said calibrations and said means having relative movement in synchronism with the movement of the record carrier.

10. A talking machine having visual means for indicating the number of records which may be played without rewinding, such means comprising an elongated sector plate, there being a slot substantially in the center thereof, reference characters on both sides of said slot, and a pointer to cooperate with the said reference characters, said pointer being mounted to travel in said slot.

11. In a record meter, the combination

of a spring motor, a dial and a pointer, means for moving one of the last two recited elements relatively to the other in one direction when the spring is unwinding, and for moving said element in the reverse direction when the spring is being wound up, said means comprising an exteriorly threaded element held against bodily movement and rotated when the spring is being wound up.

12. In a talking machine, an indicating apparatus of the class described, an elongated sector plate, there being a slot substantially in the center thereof, a scale on each side of said slot, substantially the length of said sector, an arm movable in said slot in a path parallel to the scales, a double indicating pointer carried by the arm cooperating with the said scale and adapted to traverse the scale in one direction when the motor is unwinding, and means to cause the same to travel along the slot in a reverse direction when the motor is being wound.

13. In a talking machine, a rotating record carrier and means for indicating the number of records which have been played, such means comprising indications in terms of records and an indicator, one of said last two elements being movable with the carrier relatively to the other.

14. In a talking machine, a record carrier, a spring motor therefor, means for indicating at all times the number of records which can be played by the spring with one winding, and at any time, the number of records that can still be played without rewinding, said means comprising indications in terms of records, and an indicator, one of the two being movable with the carrier relatively to the other.

15. A talking machine having an oscillating arm for indicating the spring power of the motor, a screw threaded shaft, a gear mounted on said shaft, said arm being operatively connected to the gear mounted on the screw threaded shaft, a long faced pinion in mesh with said gear and adapted to be rotated by the unwinding of the spring, the arrangement being such that the gear will be caused to travel longitudinally of the shaft in opposite directions as the spring is being unwound or rewound.

16. In a talking machine, the combination with a spring motor, a brake, a turn-table spindle, a turn-table, means for winding the motor, a gear on a screw threaded shaft, a long faced pinion in mesh therewith, means for rotating the pinion, a dial plate, a pivoted oscillating arm carrying a pointer, means actuated by the motor to cause the said arm to traverse the dial plate in one direction when the motor is unwinding, and means actuated by the winding shaft to

cause the oscillating arm to travel in a reverse direction when the motor is being wound.

17. In a talking machine, the combination with a spring motor, a brake, a winding shaft for the motor, screw threads on the shaft, a gear engaging the threads, and a long faced pinion in mesh therewith, means for rotating the long faced pinion by the 55
10 winding of the spring whereby the gear will be caused to travel longitudinally of the shaft, means actuated by the travel of the gear, of a lever pivoted to said means, an arm pivoted to the lever, a pointer on the 60
15 arm, and a scale co-operating with the pointer.

18. In a talking machine, the combination with a spring motor, means for winding the spring, and a brake lever for arresting the 70
20 unwinding of the spring, an elongated sector plate, there being a slot substantially in the center thereof, a scale on each side of said slot, substantially the length of said sector, an arm actuated by the unwinding of the 75
25 spring movable in said slot in a path parallel to the scales, a double indicating pointer carried by the arm and adapted to traverse the scale in one direction when the motor is unwinding, and means to cause the same to 80
30 travel along the slot in a reverse direction when the motor is being wound.

19. In a talking machine, the combination with a spring motor, a brake, a turn-table spindle, a turn-table, means for winding the 85
35 motor, a gear on a screw threaded shaft, a long faced pinion in mesh therewith, means for rotating the pinion, a pivoted oscillating arm carrying a pointer, and visual means co-operating with the pointer, for indicating 90
40 the number of records which may be played without rewinding, such means comprising an elongated index dial plate, having reference characters, said pointer being mounted to travel across the face of said dial.

45 20. In a talking machine, the combination with a spring motor, a brake, a winding shaft for the motor, screw threads on the shaft, a nut engaging the threads, a gear on the nut, and a long faced pinion in mesh, therewith, means for rotating the long faced 95
50 pinion by the unwinding of the spring

whereby the gear will be caused to travel longitudinally of the shaft, a yoke actuated by the travel of the gear, of a lever pivoted to the yoke, an arm pivoted to the lever, a pointer on the arm, and visual means co-operating with the pointer, for indicating the number of records which may be played without rewinding, such means comprising an elongated index dial plate having reference characters, said pointer being mounted to travel across the face of said dial. 100

21. In a talking machine, the combination with a spring motor, a turn-table spindle, an oscillating arm provided with an opening, 105
65 said arm being pivoted on said spindle to move in timed relation thereto when traveling in one direction, visual means for indicating the number of records which may be played without rewinding, such means comprising an elongated index dial plate, having reference characters, and a pointer carried by the oscillating arm, mounted to travel across the face of said dial. 70

22. In a talking machine, the combination with a spring motor, a brake, a winding shaft for the motor, screw threads on the shaft, a gear engaging the threads, and a long faced pinion in mesh therewith, means for rotating the long faced pinion by the 75
80 unwinding of the spring whereby the gear will be caused to travel longitudinally of the shaft, a yoke actuated by the travel of the gear, of a lever pivoted to the yoke, an arm pivoted to the lever, a pointer on the arm, and a scale co-operating with the pointer. 85

23. In a talking machine, the combination with a spring motor, a brake, a winding shaft for the motor, screw threads on the shaft, a gear engaging the threads, and a long faced pinion in mesh therewith, means for rotating the long faced pinion by the unwinding of the spring whereby the gear will be caused to travel longitudinally of the shaft, means actuated by the travel of the gear, of a lever pivoted to the said means, an arm pivoted to the lever, a pointer on the arm, and a scale co-operating with the pointer. 90
95

This specification signed this 15th day of May, 1915.

FRANK MALOCSAY.
